(57) **CLAIM**

The ornamental design for a trolley, as shown and described.

DESCRIPTION

FIG. 1 is a top, front, right perspective view of a trolley in an open configuration showing my new design;

FIG. 2 is a top, front, right perspective view of the trolley in a closed configuration;

FIG. 3 is a front view thereof;

FIG. 4 is a left side elevational view thereof; and,

FIG. 5 is a top plan view thereof.

The broken lines shown in the figures are included for the purpose of illustrating environment which forms no part of the claimed design.
